UNITED STATES PATENT OFFICE

EMIL DE BRUIJN, OF ROSLYN, PENNSYLVANIA

FOLDING CHAIR

Application filed June 19, 1929. Serial No. 372,131.

This invention relates to a folding chair, and relates more particularly to a folding chair having a canopy readily foldable with the chair.

5 The principal object of the invention is the provision of a chair of the indicated character which will be of simple and inexpensive construction, one which may be readily set up for use and also be readily put in folded 10 condition so as to occupy but little space when not in use.

The nature of the invention and its distinguishing features and advantages will appear when the following specification is read 15 in connection with the accompanying drawing, in which—

Figure 1 is a side view of a chair constructed in accordance with the invention.

Fig. 2 is a front view.

20 Fig. 3 is a side view of the chair folded.

Fig. 4 is a plan view of the seat.

Fig. 5 is a view of the lower portion of the back.

Fig. 6 is a detail section.

25 Fig. 7 is a detail section taken on the line 7—7, of Fig. 2.

Referring now more particularly to the drawings, it will be apparent that the chair of the present invention includes a seat 10 which may be of any preferred construction, but which will essentially be provided with slots or holes 11 occurring therein near the rear edge thereof and also being notched at the opposite front corners thereof to provide 35 shoulders or stops 12. Secured to the under side of the seat 10 at opposite sides of the seat in parallel relationship are legs 13. Legs 14 are pivotally connected respectively as at 15 with the legs 13 near the front ends thereof, and said legs 14 are respectively engageable with the shoulders or stops 12 to limit the pivotal movement of the legs 14 in one direction when the chair is set up for use. The legs 14 are connected together by a cross-bar and brace 16 at the lower ends thereof. Each leg 14 has secured to the upper end thereof a piece 17. An arm 18 is hingedly connected as at 19 with each piece 17, and the major portion of the arm projects rearwardly. A crossbar 20 has the opposite ends

thereof respectively secured to the rear extremities of the arms 18. A back 21 is hingedly connected as at 22 with the crossbar 20. The back 21 may be of any preferred construction, and includes a top piece 23 which projects a suitable distance at each side of the back. The back 21 also has lugs 24 on the lower edge thereof which are respectively receivable in the slots or holes 11 in the seat 10 in order to retain the parts against unintentional relative movement when said parts are arranged in chair forming relationship, as shown in Figs. 1 and 2.

In accordance with another feature of the invention the chair is provided with a canopy attachment. The attachment includes a piece of canvas or other similar material 25. The rear edge of the piece of canvas 25 is fastened to the top piece 23 of the back by strips 26 and 27 secured to the top piece 23, by suitable fastening elements, as shown most clearly in Fig. 6. The piece of canvas 25 is supported at the front by a metal frame of U-shape. This frame therefore consists of side members 28 connected by a cross member 29. The piece of canvas 25 is folded upon itself and is stitched to provide a hem or tunnel 3 which receives the cross member 29. The lower end 30 of each side member 28 is bent at an angle with respect to the major portion of the member, and extends in a tapered hole 31 in the related arm 18, and also is threaded to receive a nut 32. Each end of the crossbar 20 is beveled as at 33 to enable the insertion of the end 30 of the related side member into the hole 31. It will now be apparent that the canopy frame will be associated with the arms 18 and cross bar 20 in such a manner that the side members 28 will abut the beveled ends 33 while the ends 30 will engage the arms 18, to maintain the piece of canvas 25 taut, when the parts are in the chair forming relation. Each of the side members 28 of the frame has an offset 34 in order that the frame may be brought to the proper folded position, and also to obtain the proper distance between the cross member 29 and the strip 26 when the chair is set up for use.

In order to set up the chair, one of the legs

13 is gripped with one hand and one of the legs 14 is gripped with the other hand and pivotal movement may thus be imparted to the legs, until the legs 14 engage the stops or shoulders 12. The arms 18 may then be swung on their hinges 19 by imparting movement to the back 21, the latter meanwhile swinging on its hinges 22. The back 21 is brought to a position in which the lugs 24 are engaged in the holes 11 in the seat 10. Incidental to this last operation, the canopy frame will be swung to a position in which the piece of canvas 25 will be stretched, due to the fact that the lower ends of the side members 28 will abut the beveled ends 33 of the crossbar 20, while the ends 30 engage the arms 18. The chair is then ready for use.

When it is desired to collapse the chair, the back 21 is lifted to disengage the lugs 24 from the holes 11, after which a forward push on the back 21 will cause pivotal movement of the front legs 14, and relative movement of the arms 18 with respect to the front legs 14 by reason of the hinges 19, and relative movement of the back 21 with respect to the arms 18 by reason of the hinges 22 between the crossbar 20 and the back 21. In the collapsed condition the parts will assume the relationship shown in Fig. 3.

It is to be understood that the canopy attachment of the chair may be omitted, in which case, the chair will be manufactured having the other features set forth, with the further understanding that the construction of the back may be altered and the size thereof reduced to be in proper proportion.

I claim:

1. A folding chair comprising a seat provided with holes near the rear edge thereof and stops at the sides, legs secured to said seat, front legs pivoted to the first mentioned legs and engageable respectively with said stops, an arm hingedly connected with each front leg, a crossbar connecting the rear ends of said arms, a back hingedly connected with said crossbar, and lugs on the lower edge of said back engageable respectively in the holes in said seat.

2. A folding chair comprising a seat provided with holes near the rear edge thereof, and being notched to present shoulders at the sides, legs secured to the underside of said seat at opposite sides in parallel relation, front legs pivoted to the first mentioned legs and engageable respectively with said shoulders, an arm hingedly connected with each front leg, a crossbar connecting the rear end of said arms, a back hingedly connected with said crossbar, and lugs on the lower edge of said back engageable respectively in the holes in said seat.

3. The combination with a folding chair including a back and arms and means hingedly connecting them together; of a canopy for the chair comprising a frame, and a piece

of flexible material, said frame having side members and a connecting cross member, the rear end of said piece of flexible material being fastened to the top of said back and the front end thereof being connected with said cross member, and the lower ends of the side members being pivoted to said hinge means.

EMIL DE BRUIJN.
